UNITED STATES PATENT OFFICE.

WALDO A. RICH, JR., AND CHARLES C. WILLIS, OF SOUTH FRAMINGHAM, MASSACHUSETTS, ASSIGNORS TO DENNISON MANUFACTURING COMPANY, OF BOSTON, MASSACHUSETTS, A CORPORATION OF MASSACHUSETTS.

CABINET FOR PAPER-PACKAGES.

1,181,613.

Specification of Letters Patent.

Patented May 2, 1916.

Application filed October 12, 1915. Serial No. 55,553.

To all whom it may concern:

Be it known that we, WALDO A. RICH, Jr., and CHARLES C. WILLIS, citizens of the United States, and residents of South 5 Framingham, in the county of Middlesex and State of Massachusetts, have invented new and useful Improvements in Cabinets for Paper-Packages, of which the following is a specification.

10 This invention relates to holders or cabinets for paper packages of the general class formed of a plurality of sheets adapted for use as towels or the like, folded in compact form, the sheets of the package being so 15 organized and arranged that they may be withdrawn from the cabinet one at a time, the removal of one sheet causing the sheet adjacent thereto automatically to be brought to a position where it may be readily 20 grasped and removed.

More particularly the invention relates to a holder or cabinet having a vertical front in which the dispensing opening is located, and in which the sheets of the package stand 25 on their folded edges with the free end of the sheet adjacent to the opening projecting or depending therefrom.

In a holder or cabinet of this type it is necessary to provide a follower to hold the 30 stacked sheets flat and press the package as a whole against the front of the cabinet as the sheets are successively withdrawn; and it is the principal object of this invention to provide a follower which will effectively 35 press the package against the cabinet front and at the same time will not interfere with the filling or reloading of the cabinet or require extensive manipulation in readjustment for use after the cabinet has been 40 filled.

Other objects of the invention will be hereinafter more particularly referred to.

Referring to the drawings which illustrate an embodiment of the invention,— 45 Figure 1 is a central, vertical section of the improved cabinet; Fig. 2 is a section on the line 2—2, Fig. 1; Fig. 3 is a view similar to Fig. 1, showing the cabinet in open position; and Fig. 4 is a perspective view of a 50 sheet of the paper package.

A is the body of the cabinet or holder, having a vertical front provided with a dispensing opening A'. The back cover B, which in the example shown, is adapted to

be secured to a wall or other support (Fig. 55 3) is provided with inturned flanges B' pivoted at their lower ends to the side walls of the cabinet body, and has at its top a spring catch C adapted to engage a complementary member C' on the top wall of the 60 body yieldingly to lock said cover and body in normal closed position, as shown in Fig. 1.

Between the inwardly turned flanges B' and near the top edge of the cover B, there 65 is rigidly secured a rod D on which is mounted a pair of coiled follower springs E spaced apart (Fig. 2) and having their ends e in engagement with said back cover. Chains F are secured at one end to the bottom of the cabinet body in close proximity to the front wall, the opposite ends thereof being secured to the ends of the free arms E' of the springs E, so that there is thus 70 provided a flexible connection between said 75 arms E' and the cabinet body. Preferably, as shown, recesses A² are provided in the bottom of the body A, in which said chains may rest and thus be out of engagement 80 with the paper package P, hereinafter described, and which rests upon said bottom.

The paper package P, adapted to be contained within the body, preferably consists of a plurality of sheets, each folded to form a long section p and a single short section 85 p', said sheets being superposed to form the package, the short section of each sheet being in juxtaposition with the long section of the adjacent sheet, said sheets standing on their folded edges with the short sections 90 in front, the free end of the short section of the front sheet terminating between the top and bottom edges of the dispensing opening A' so that it may project or depend 95 therefrom. This package it will be understood is one wherein the removal of the front sheet causes the sheet adjacent thereto automatically to be brought to a position where it can be readily grasped and removed; and it will be further understood 100 that while the package shown and described is preferred, other packages wherein the sheets are so organized and arranged that the removal of the front sheet causes the adjacent sheet automatically to be brought 105 into position to be grasped and withdrawn from the cabinet, may be employed.

G is a follower adapted to rest against

the last or back sheet of the package P, and to be tightly held in position by the spring follower arms E' which engage it when the cabinet is in normal closed position, as shown in Fig. 1. It will be clear that the pressure of the spring arms E' against the follower G holds the stacked sheets flat, and presses the package as a whole against the front of the cabinet body, the flexible connections F permitting the spring arms E' to move forward in engagement with the follower plate as the sheets are successively removed.

When the package P has been exhausted, the cabinet body A is swung down into the position shown in Fig. 3 for the insertion of a new paper package, and the chains F actuated by said downward movement withdraw said arms out of the path in which the package is to be inserted, as clearly shown in said Fig. 3. To refill or reload the cabinet, therefore, it is necessary merely to swing the body downward, remove the follower G, insert a new package P, replace the follower upon it, and swing the body of the cabinet A back into normal closed position, where it is ready for use with the follower springs in engagement with the follower without the necessity of manipulation of the follower springs to force them out of or into working position.

As the sheets of the tightly pressed package are successively withdrawn, there is a gradual lifting of the sheets, particularly near the cabinet front, which, if un prevented, results in short sheets p' being lifted to such an extent that before the package is exhausted their free ends instead of terminating between the top and bottom edges of the dispensing opening A' extend above said top edge so that the front sheet cannot fall or project from said opening, and so become readily available for use. To eliminate this difficulty the opposite side walls of the cabinet body are provided near the front with projections or holders H, adapted frictionally to engage the vertical edges of the sheets and check or restrain their upward movement. Preferably these projections are located at a short distance from the cabinet bottom and are wedge-shaped, as shown, the bases of the wedges being toward the front of the cabinet where the tendency of the sheets to lift is greatest and where, therefore, the strongest restraint is required. As the points of the wedges are toward the back of the cabinet body, said wedges offer no obstruction to the insertion of the paper package into the cabinet, the sheets thereof readily sliding along the inclined surfaces into position against the cabinet front.

We claim:—

1. A cabinet for paper packages, comprising body and cover members relatively

movable to permit the insertion of a package into said body, a follower spring and means adapted to be actuated by the opening movement of said members to withdraw said spring out of the path in which said package is inserted. 70

2. A cabinet for paper packages, comprising body and cover members relatively movable to permit the insertion of a package into said body, a follower spring, means to withdraw said spring out of the path in which said package is inserted and means adapted to be actuated by the closing movement of said members to release said spring to permit its return to working position. 80

3. A cabinet for paper packages, comprising body and cover members relatively movable to permit the insertion of a package into said body, a follower spring, and means adapted to be actuated by the opening movement of said members to withdraw said spring out of the path in which the package is inserted, and to release said spring to permit its return to working position upon the closing movement thereof. 85

4. A cabinet for paper packages, comprising body and cover members relatively movable to permit the insertion of a package into said body, a follower spring mounted on one of said members and a connection between said spring and the other of said members, adapted to be actuated by the opening movement of said members to withdraw said spring out of the path in which said package is inserted. 90

5. A cabinet for paper packages, comprising body and cover members relatively movable to permit the insertion of a package into said body, a follower spring mounted on one of said members, and a flexible connection between said spring and the other of said members, adapted to be actuated by the opening movement of said members to withdraw said spring out of the path in which said package is inserted. 105

6. A cabinet for paper packages, comprising body and cover members relatively movable to permit the insertion of a package into said body, a follower spring mounted on one of said members, means to withdraw said spring out of the path in which said package is inserted and a connection between said spring and the other of said members, adapted to be actuated by the closing movement of said members to release said spring to permit its return to working position. 115

7. A cabinet for paper packages, comprising body and back cover members relatively movable to permit the insertion of a package, a follower, a follower spring mounted on said cover, and a connection between said spring and said body adapted to be actuated by the opening movement of said members to withdraw said spring out of the path in which the package is inserted. 125

8. A cabinet for paper packages, comprising body and back cover members relatively movable to permit the insertion of a package, a follower, a follower spring mounted on said cover, and a flexible connection between said spring and said body adapted to be actuated by the opening movement of said members to withdraw said spring out of the path in which the package is inserted.
- 10 9. A cabinet for paper packages, comprising body and back cover members relatively movable to permit the insertion of a package into said body, a follower, a coiled follower spring mounted on said back and having an arm and a connection between said body and said spring arm adapted to be actuated by the opening movement of said members to withdraw said spring arm out of the path in which said package is inserted.
- 15 10. A cabinet for paper packages, comprising body and back cover members relatively movable to permit the insertion of a package into said body, a follower, a rod mounted on said cover and provided with a pair of coiled springs having arms, and connections between said body and said arms adapted to be actuated by the opening movement of said members to withdraw said arms out of the path in which said package is inserted.
- 20 11. A cabinet for paper packages, comprising body and back cover members relatively movable to permit the insertion of a package into said body, a follower, a coiled follower spring mounted on said cover and provided with a
- 25 pair of coiled springs having arms, and connections between said body and said arms adapted to be actuated by the opening movement of said members to withdraw said arms out of the path in which said package is inserted.
- 30 12. A cabinet for paper packages, comprising a vertical front provided with a dispensing opening, and means adapted frictionally to engage the lateral edges of the sheets of the package to restrain upward movement of said sheets.
13. A cabinet for paper packages, comprising a vertical front provided with a dispensing opening, and a projection on the side wall of said cabinet to restrain the upward movement of the sheets of the package.
14. A cabinet for paper packages comprising a vertical front provided with a dispensing opening, and a projection on the side wall of said cabinet adapted frictionally to engage the lateral edges of the sheets of the package to restrain upward movement of said sheets.
